UNITED STATES PATENT OFFICE.

CHARLES L. HEISLER, OF ST. MARYS, OHIO.

CHURN.

No. 887,800.

Specification of Letters Patent.

Patented May 19, 1908.

Application filed June 5, 1907. Serial No. 377,447.

To all whom it may concern:

Be it known that I, CHARLES L. HEISLER, a citizen of the United States, residing at St. Marys, in the county of Auglaize and State of Ohio, have invented certain new and useful Improvements in Churns of the Rotary-Dasher Type, and which are described in the following specification and illustrated by the accompanying drawings.

10 Figure 1 shows a longitudinal elevation. Fig. 2 shows an end elevation. Fig. 3 shows a vertical cross section. Fig. 4 shows a top view. Fig. 5 shows a section of the enlarged stave. Fig. 6 shows a section of the 15 cross piece.

The primary object of my invention is to provide a more effective and desirable construction and arrangement of driving gear and to provide a more durable and readily 20 cleaned churning chamber.

Heretofore it has been usual to construct barrel churning chambers with a contracted opening, which would not readily permit cleaning or removing the butter from the 25 churn. Furthermore, in rotary dash churning chambers it has been usual to construct a chamber having a very large opening in the top and therefore requiring a very large lid, which, because of its size, was expensive and readily warped. 30 Moreover, this old form of churn was difficult to keep tight. In this new construction the maximum volume is obtained with a minimum expenditure of material like in the barrel churn, at the same time, however, it gives 35 accessibility with medium size of opening, thereby avoiding the objectionable feature of the older types of churns.

Heretofore, it has been impossible to put grease on the churn gears because of the 40 danger to clothing and to the contents of the churn. Moreover, considerable injury has been caused by the unguarded gears to children and clothing. These defects are eliminated in the new device as will be shown 45 hereinafter.

In the several figures, numeral 1 is the churning chamber. 2 and 3 the staves forming the cylindrical wall. 4 and 4' the end heads that fit in grooves formed in the staves. 50 5 the lid.

The churn chamber 1 is supported upon a tripod formed by the legs 6 and the supporting casting or keel 7, upon which are formed sockets or lugs to secure the legs as shown. 55 A drip catching lip 8 is formed upon this keel

casting, likewise several lugs 9; these have suitable holes to retain the adjustable hoops or rods 10 and 10' which are fitted with adjusting nuts or screws 11 as shown. These rods, in combination with the said tripod, 60 form a very rigid and strong support for the chamber. The rods also form a ready means for adjusting the tightness of the churn.

The staves 3 are especially constructed with an enlarged upper edge as shown in Fig. 65 5 to give a strong rim for the opening. The rods 10 are made to pass through holes 12 that are drilled through and near the upper edge of the staves 3, thence said rods pass between the heads 4 and 4', and the cross 70 pieces 13. The latter having a suitable retaining groove formed on their under side to inclose the rods as shown. The opposite ends of the rods 10 meet at the supporting keel 7 and thereby form complete adjustable 75 hoops that tightly hold the staves and heads in place. The short rods 10' terminate in the staves 3 as shown in Fig. 3 and Fig. 5. The cross pieces 13 are fastened by screws to the heads 4 and butt at right angles against 80 the staves 3, forming a strong and complete rectangular rim about opening, at the same time protecting the iron hoops or rods from contact with the contents of the chamber.

The dasher 14 is of usual construction, excepting that an enlargement 15 is formed on the upper end of its wooden shaft as shown in Fig. 1 to prevent the liquids from splashing through the opening 16 and to avoid slipping through the operator's hand when inserting 90 it into the flanged spool 17. This spool is flanged for the purpose of preventing oil from flowing into the churn from the spindle bearing 18. To further prevent this, a wiper 19 is placed in contact with the flange of the spool 95 as shown in Fig. 1.

At the upper end of the inclined dasher spindle is arranged a bevel pinion 20 that is actuated by meshing with the internal bevel wheel 21, which is operated by any suitable 100 crank or power. This internal bevel wheel is mounted upon a removable pin 22 that is removably fastened to the gear bracket 23. The internal wheel 21 is cast preferably without spokes, so the pinion 20 is completely 105 guarded by the oil tight saucer shaped internal gear wheel. The bracket 23 also forms a shield at the back of the gear, thereby forming a complete protection against injury to children or clothing.

A lip 24 collects any drippings from the bearings and returns them into the internal gear wheel, the axis of which forms an acute angle with the dasher shaft or spindle as shown. Lugs 25 are formed on the bracket 23 to more firmly hold the gearing on the churn.

In Fig. 1 it will be seen that when the crank handle is carried by gravity to its lowest and natural position, the thumb nut or clamping screw on the spool 17 is in its upward and most accessible position. This saves a great deal of annoyance when removing or replacing the dasher, and is effected by having the number expressing the pinion and gear teeth ratio a whole number, for example, as 3 to 1, and by setting the gears as shown.

What I claim is:

1. The combination of a churning chamber, a revolving inclined dasher arranged therein with its lower end free and in such a manner that its dasher spindle passes at an acute angle through an opening arranged at the upper end of the chamber at the juncture 25 of the cover and side wall of said chamber, a bevel pinion attached to the upper end of said dasher spindle, a bevel gear wheel actuated by a crank and meshing with and driving said pinion; said bevel gear wheel having 30 its axis arranged horizontally at an acute angle with said dasher spindle, of a gear bracket attached directly to said side wall but free from said cover and located between said gears and said churning chamber, there being 35 a projecting and horizontally arranged gear wheel bearing formed on said bracket to support the bevel wheel, and another bearing at its upper end for said dasher spindle and placed at some distance above said chamber 40 at an acute angle with said gear wheel bearing for the purpose described.

2. The combination of a churning chamber, a revolving dasher arranged therein in such a manner that its dasher spindle passes 45 at an acute angle through an opening arranged at the upper end of the chamber, a bevel pinion attached at the upper end of said spindle, an internal bevel gear wheel inclosing and meshing with said pinion, the 50 axis of which wheel making an acute angle with said dasher spindle, of a bracket attached to said chamber and forming supporting bearings for said spindle and gears for the purpose described.

55 3. The combination of a churning chamber, a revolving dasher arranged therein in such a manner that its dasher spindle passes at an acute angle through an opening arranged at the upper end of the chamber, a bevel pinion attached at the upper end of said spindle, an internal bevel gear wheel inclosing and meshing with said pinion, the 60 axis of which wheel making an acute angle with said dasher spindle, of a bracket attached to said chamber and forming support-

ing bearings for said spindle and gears, there being a shield formed on said internal bevel gear for the purpose described.

4. The combination of a churning chamber, a revolving dasher arranged therein in such a manner that its dasher spindle passes at an acute angle through an opening arranged at the upper end of the chamber, a bevel pinion attached at the upper end of said spindle, a bevel gear wheel meshing with 75 said pinion, a bracket attached to said chamber and forming supporting bearings for said spindle and gears, said spindle having a disk or flange 17 formed thereon for the purpose of preventing oil from entering the churn. 80

5. The combination of a churning chamber, a revolving dasher arranged therein in such a manner that its dasher spindle passes at an acute angle through an opening at the upper end of the chamber, a bevel pinion attached at the upper end of said spindle, a bevel gear wheel meshing with said pinion, a bracket attached to said chamber and forming supporting bearings for said spindle and gears, of a spool attached to said spindle and having a disk or flange formed thereon and means for clamping said spool to the dasher for the purpose described.

6. The combination of a churning chamber, a revolving dasher arranged therein in such a manner that its dasher spindle passes at an acute angle through an opening at the upper end of the chamber, a bevel pinion attached at the upper end of said spindle, a bevel gear wheel meshing with said pinion, a 100 bracket attached to said chamber and forming supporting bearings for said spindle and gears, of a spool attached to said spindle and having a disk or flange formed thereon and an oil wiper engaging with said flange for the purpose described.

7. The combination of a churning chamber, a revolving dasher arranged therein in such a manner that its dasher spindle passes at an acute angle through an opening arranged at the upper end of the chamber, a bevel pinion attached at the upper end of said spindle, a bevel gear wheel meshing with said pinion, the axis of said wheel making an acute angle with said dasher spindle, of a 110 bracket attached to said chamber and forming supporting bearings for said spindle and gears, said bracket having lugs 25 forming gibbs formed thereon to engage with the walls of the chamber for the purpose described. 120

8. The combination of a churning chamber, a revolving dasher arranged therein in such a manner that its dasher spindle passes at an acute angle through an opening arranged at the upper end of the chamber, a bevel pinion attached at the upper end of said spindle, an internal bevel gear wheel inclosing and meshing with said pinion, the 125 axis of said wheel making an acute angle with said dasher spindle, of a bracket forming sup- 130

porting bearings for said spindle and gears, and attached to said chamber, and a removable projecting pin 22 attached to said bracket and forming the internal gearwheel bearing 5 for the purpose described.

9. The combination of a churning chamber, a revolving dasher arranged therein in such a manner that its dasher spindle passes at an acute angle through an opening arranged 10 at the upper end of the chamber, a bevel pinion attached at the upper end of said spindle, an internal bevel gear wheel inclosing and meshing with said pinion, the axis of said wheel making an acute angle with 15 said dasher spindle, of a bracket attached to said chamber and forming supporting bearings for said spindle and gears, there being a lip formed on said bracket and arranged to project into said internal bevel wheel for the 20 purpose described.

10. The combination of a churning chamber, a revolving dasher arranged therein in such a manner that its dasher spindle passes at an acute angle through an opening arranged 25 at the upper end of the chamber, a bevel pinion attached at the upper end of said spindle, an internal bevel gear wheel inclosing and meshing with said pinion, the axis of said wheel making an acute angle with 30 said dasher spindle, of a bracket attached to said chamber and forming supporting bearings for said spindle and gears, there being a shield 23 formed on said bracket, back of the internal gear, to cover the inclosed pinion in 35 the manner described.

11. The combination of a cylindrical churning chamber, a dasher arranged therein, means for actuating said dasher, a supporting casting or keel, adjustable clamping hoops or 40 rods attached to said supporting casting and passing around said chamber, there being lugs or sockets formed on said supporting casting or keel for securing the legs for the purpose described.

45 12. The combination of a cylindrical churning chamber, a dasher arranged therein, means for actuating said dasher, a supporting keel, adjustable clamping hoops or rods attached to said supporting keel and passing 50 around said chamber, there being lugs or sockets formed on said supporting keel for securing the legs, said keel being provided with a lip for the purpose described.

13. The combination of a cylindrical 55 churning chamber with its axis placed horizontally, a dasher arranged therein, means for actuating said dasher, adjustable clamping hoops, staves arranged within these rods or hoops, heads fitted into grooves formed at 60 the opposite ends of said staves, there being an opening formed in the top side of the

cylindrical wall, the two sides of said opening, which are parallel with the axis of said chamber, being formed by two enlarged staves, which are materially enlarged on 65 their top edges, thereby forming the rim of the opening, the lower edge of said staves matching the other staves, and the pair of cross-pieces (13) and (13) arranged at right angles to and between the said enlarged 70 staves, at opposite sides of the opening, and on top of the heads, thereby forming a complete rectangular rim of extra strength for the opening, as described.

14. The combination of a cylindrical 75 churning chamber with its axis placed horizontally, a dasher arranged therein, means for actuating said dasher, adjustable clamping hoops, staves arranged within these rods or hoops, heads fitted into grooves formed at 80 the opposite ends of said staves, there being an opening formed in the top side of the cylindrical wall, the two sides of said opening, which are parallel with the axis of said chamber, being formed by two enlarged 85 staves, which are materially enlarged on their top edges, thereby forming the rim of the opening, the lower edge of said staves matching the other staves, and the pair of cross-pieces (13) and (13) arranged at right 90 angles to and between the said enlarged staves, at opposite sides of the opening, and on top of the heads, thereby forming a complete rectangular rim of extra strength for the opening, the said adjustable rods being 95 made to pass through holes formed in the enlarged staves and between the cross-pieces and heads for the purpose described.

15. The combination of a churning chamber, a revolving inclined dasher arranged 100 therein with its lower end free and in such a manner that its dasher spindle passes at an acute angle through an opening arranged at the upper end of the chamber at the juncture of the cover and side wall of said chamber, a 105 bevel pinion attached to the upper end of said dasher spindle, a bevel gear wheel actuated by a crank and meshing with and driving said pinion; said bevel gear wheel having its axis arranged horizontally at an acute 110 angle with said dasher spindle, the number of gear teeth in said wheel being an exact multiple of those contained on the pinion, of a clamping screw for attaching the dasher to the spindle and set so it will always be in a 115 convenient position when the crank handle is in its lower position, as described.
